UNITED STATES PATENT OFFICE.

JOHN LESLIE ADAMS, OF CHICAGO, ILLINOIS.

DESIGN FOR A PEN FOUNTAIN.

60,924.

Specification for Design.

Patented May 2, 1922.

Application filed January 3, 1921. Serial No. 434,815. Term of patent 7 years.

To all whom it may concern:

Be it known that I, JOHN LESLIE ADAMS, a citizen of the United States, residing at Chicago, in the county of Cook and State of Illinois, have invented a new, original, and ornamental Design for Pen Fountain, of which the following is a specification, reference being had to the accompanying drawing, forming part thereof.

The figure is a side elevation of a pen fountain, as shown operatively applied to a pen.

I claim:

The ornamental design for a pen fountain, as shown.

JOHN LESLIE ADAMS.
